UNITED STATES PATENT OFFICE.

THOMAS WINFRED SOUTH, OF DE KALB, ILLINOIS, ASSIGNOR OF ONE-HALF TO ROY A. GILBERTSON, OF DE KALB, ILLINOIS.

TIME-CONTROLLED MECHANISM FOR OPERATING ELECTRIC SWITCHES.

1,350,389.

Specification of Letters Patent. Patented Aug. 24, 1920.

Application filed March 6, 1917. Serial No. 152,614.

To all whom it may concern:

Be it known that I, THOMAS W. SOUTH, a citizen of the United States, and a resident of the city of De Kalb, county of Dekalb, and State of Illinois, have invented certain new and useful Improvements in Time-Controlled Mechanism for Operating Electric Switches, of which the following is a specification.

My invention relates to improvements in time controlled mechanism for operating or controlling electric switches, and has for its object the production of a mechanism of this character, which will be of durable and economical construction, positive in operation, one which will permit of ready adjustment to vary the times or periods of throwing in or out of the switch controlled thereby, and one which will be highly efficient in use.

Other objects will appear hereinafter.

The invention consists in the combinations and arrangements of parts hereinafter described and claimed.

The invention will be best understood by reference to accompanying drawings, forming a part of this specification, and in which—

Figure 1 is a front elevation of a switch-controlled mechanism, embodying the invention,

Fig. 2, a side elevation thereof,

Fig. 3, a front elevation of one of the gears and an associated perforated disk included in the construction,

Fig. 4, a central section through the construction shown in Fig. 3,

Fig. 5, a detail side elevation of another part of the mechanism,

Fig. 6, a section through the construction shown in Fig. 5, and

Fig. 7, a partially sectional side elevation of the switch shown in Figs. 1 and 2.

The preferred form of construction as illustrated in the drawings, comprises a clock work 1 of any ordinary or preferred design, the hour hand arbor of said clock work being shown at 2.

Arranged above the clock work is a conventional form of a rotary electric switch 3, conductor wires of the circuit in which said switch is interposed being shown at 3'. Said switch is mounted upon a bracket 4

which, in turn, is secured to a bracket 5 rigidly fastened to the supporting frame work 6 of the clock work 1. The bracket 4 is positioned at the rearward side of the switch, and in order to support the front end of the switch, a supplemental supporting arm or bracket 4' is provided in which the outer end of the rotary stem 7 of the switch is rotatably mounted, as clearly shown in Fig. 7.

The outer end of the stem 7 is threaded, and ordinarily carries a finger piece or turn button, whereby the switch is operated, this finger piece or turn button, where the switch is arranged for control by time mechanism, being removed and a tubular end piece 8 arranged in its place, as clearly seen in Fig. 7. The member 8 is formed with a ratchet wheel 9 having four equally spaced teeth, a screw 10 threaded in the outer end of member 8 and which is adapted to engage with the end of stem 7, serving as a means of positively locking said member 8 in position. Coöoperating with the ratchet 9 is a pawl 11 carried by an oscillatory arm 12, one end of which pivotally engages with the end piece 8. A leaf spring 13 coöperates with the pawl 11 for normally pressing the same into operative relation with ratchet 9. The free end of arm 12 is operatively connected by means of a link 14 with the outer end of an arm 15 pivotally engaging with the reduced outer end of a tubular post 16 secured by means of a screw 17 to the bracket 5. The outer end of arm 12 is formed with a plurality of spaced openings 18 in order to allow for adjustment in the connection of the link 14 therewith, so as to secure proper timing in the operation of the switch, as will be readily understood.

Also pivotally mounted upon the reduced outer end of the post 16 is an arm or trigger 19 which, together with the arm 15, is locked in position by screw 17. The arm 19 is formed with a stop lug 20 adapted to engage against the under side of arm 15 to limit pivotal movement of the arm 19 in a clockwise direction. A helical tension spring 21 coöperates with the arm 19 to normally hold the same in a position with the lug 20 thereof, engaging against arm 15. With this arrangement it will be seen that the arm 19

is adapted to yield in a counter clockwise direction but, when moved in the opposite direction, the same will impart oscillatory movement to the arm 15, the latter, in turn, 5 through the link 14 and arm 12, effecting operative movement of the pawl 11 which, through engagement with the ratchet 9, will effect operation of the electric switch.

This operative movement of the arm 19 10 is effected through the medium of a gear 22 which is loosely mounted upon a tubular post 23 secured by means of a screw 23' to supporting bracket 5. Mounted upon the hub of the gear 22 for free rotary movement 15 thereon is a disk 24 adapted to be locked in positions of rotary adjustment, relative to said gear, by means of a screw 25 threaded in said disk and which is adapted to engage at its inner end against the hub 20 of said gear. Carried at the front side of disk 24 is a plurality of spaced studs 26 which are adapted to engage at their inner ends with any of a plurality of spaced perforations 27 formed in disk 24, and ar- 25 ranged in annular formation close to the periphery of said disk. The studs 26 are adapted to be locked in engagement with sockets 27 by means of screws 28, there being threaded openings formed in the 30 periphery of said disk for engagement of said screws. The studs 26, as will be seen, are arranged in the path of arm 19 so that upon rotation of disk 24, said studs will successively engage with said arm and 35 thereby effect operative movement of the same which, in turn, will cause operation of the switch 3. By providing a plurality of sockets 27, provision is made for adjustment of the studs 26 in order to effect operation 40 of the switch at any time or interval desired. The arrangement is such that successive operations of the switch caused by intermittently rotating the switch stem, effects alternate opening and closing of the 45 switch, so that in the operation of the mechanism, one of the studs 26 will effect opening of the switch and the other closing of the same. The arrangement is such that each actuation of the 50 arm 19 by one of the studs 26 causes the ratchet to be stepped up one tooth, the pawl 11, after each operation, dropping back behind the next rearward tooth of the ratchet. Through rotary adjustment of the 55 disk 24 which is permitted upon loosening of screw 25, the period or time of operation of the switch may, as will be seen, also be controlled, and through the loose pivoting of the pawl 19 in one direction the disk may 60 be rotatably adjusted in a clockwise direction without fear of the studs 26 effecting any operative movement of said pawl 19.

To alleviate friction in the contact of the studs 26 with the pawl 19, said studs are pref- 65 erably provided with rollers 26' which con-

tact with the arm 19, as clearly seen in Fig. 2.

The switch operating mechanism thus de- 70 scribed is operatively connected with the clock work 1 through the medium of a train of gears 29, 30 and 31 which connect the gear 22 with the arbor 2 of the clock work, as clearly seen in Figs. 1 and 2.

With a mechanism as described it will be 75 seen that the opening and closing of an electric circuit, such as of the hall lights in an apartment building, the lights of an illuminating sign and the like may be automatically controlled, the only manual attention which need be given to the mechanism 80 being the winding of the clock work spring and adjustment of the parts of the switch operating mechanism to secure the opening and closing of the switch circuit at the proper intervals. 85

While I have illustrated and described the preferred form of construction for carrying my invention into effect, this is capable of variation and modification without departing from the spirit of the in- 90 vention. I, therefore, do not wish to be limited to the precise details of construction set forth, but desire to avail myself of such variations and modifications as come within the scope of the appended 95 claims.

Having described my invention what I claim as new and desire to secure by Letters Patent is:

1. A mechanism for controlling a rotary 100 electric switch comprising a clock work; an oscillatory arm adapted, when actuated, to operate said switch; means for actuating said arm, said means comprising a rota- 105 ble shaft, a disk mounted on said shaft, so as to be adjustable thereon around its axis; means for securing said disk in its positions of adjustment on said shaft; a plurality of engaging elements on said disk adapted, upon rotation of the latter, to en- 110 gage with and actuate said arm; and an operative connection between said clock work and said disk, substantially as de- 115 scribed.

2. A mechanism for controlling a rotary 115 electric switch comprising a clock work; an oscillatory arm; a ratchet on the stem of said switch; a pawl carried by said arm for co-operation with said ratchet and adapted, upon oscillation of said arm, to effect inter- 120 mittent rotary movement of said switch stem; means of oscillating said arm comprising a second oscillatory arm; a link connecting said arms; a third oscillatory arm operatively connected with said second arm; rotary means for operating said third arm; and an operative connection between said last mentioned means and said clock work, substantially as described. 125

3. The combination of a rotary electric 130

switch having a threaded stem, of a sleeve applied to said stem; a screw threaded into said sleeve and engaging against said stem for locking said sleeve and stem together; a ratchet on said sleeve; a clock work; and an operative connection between said clock work and said ratchet, substantially as described.

In testimony whereof I have signed my name to this specification in the presence of 10 two subscribing witnesses.

THOMAS WINFRED SOUTH.
